SEPTUM

Filed June 4, 1927

Fig. 1.

UNITED STATES PATENT OFFICE

BENJAMIN WOODWARD HAZELL, OF BALTIMORE, MARYLAND

SEPTUM

Application filed June 4, 1927. Serial No. 196,537.

The present invention relates to optical instruments, and particularly to an attachment for various types of vision testing and measuring instruments such as test frames, 5 refractionmeters, phorometers and optometers in general.

An object of the invention is to provide a removable and adjustable attachment for converting such instruments into means for 10 testing the eyes for binocular vision.

More specifically, it is an object of the invention to provide such an attachment so constructed as to be readily attached and detached, and, in addition, when attached, 15 readily adjusted longitudinally, and quickly moved angularly and held in either operative or vertical position or in inoperative or horizontal position.

Other objects and advantages of the invention will appear from the following description, taken in connection with the accompanying drawings, wherein is shown a preferred embodiment thereof associated with one common form of optical instrument, 20 which, by means of the present invention, can be readily converted into a stereoscope for the purpose of testing the eyes for binocular vision and also for the purpose of giving fusional and muscular exercise to the 25 eyes.

The invention consists in the septum and in the means and mechanism associated therewith, as defined by the appended claims.

In the drawings:

Fig. 1 is a perspective view of a refractionmeter, showing the attachment thereto of the invention;

Fig. 2 is an enlarged side elevation of the 40 septum, in vertical position and attached to the card frame bar;

Fig. 3 is a vertical section taken on the line 3—3 of Fig. 2;

Fig. 4 is a perspective view of the fixed 45 pivot rod of the septum; and

Fig. 5 is a perspective view of another form of securing means.

Referring in detail to the accompanying 50 drawings, for the purpose of illustrating the attachment and use of the invention, an

ordinary form of refractionmeter has been shown by way of example, though it will be understood that the invention and its advantages are equally applicable to other refractionmeters or phorometers or similar 55 optical testing, exercising or measuring instruments.

The refractionmeter here shown by way of example comprises a base 11, a vertically adjustable front standard 12 secured to the 60 base and carrying a chin rest 13, lens supports 14 and 15, and lenses 18 and 19. A vertically adjustable rear standard 20 is secured at its lower end to the base 11 and carries at its upper end the horizontally extending rod or bar 21, upon which is slidably mounted a card frame 22.

The present invention, as stated, includes a septum, and provides means associated therewith for supporting it and permitting 70 quick horizontal adjustment, quick attachment and detachment, and means whereby the septum, when attached, can be readily moved to operative or inoperative position.

Accordingly, the septum 26, which is 75 preferably opaque, is rigidly secured to an angularly movable hinge member 27, which is formed for the reception of a pin or rod 29 (see Fig. 4). The rod 29 is provided intermediate its ends with the vertically extending offset portion 31, which, in the vertical position of the septum 26, is adapted to extend into the vertical pocket 32 formed interiorly of the movable hinge member 27, and, in the inoperative or approximately horizontal position of the septum, is adapted to extend into one or the other of the lateral pockets 35 and 36, likewise formed interiorly of the movable hinge member 27. The hinge member 27 is 80 preferably formed of two substantially flat complementary pieces of metal, secured together by rivets or eyelets 39, and having sufficient spring to permit the offset portion 31 to ride past the shoulders 40, and from one receiving pocket to another, when relative movement occurs between the septum 26 and rod 29, as when the septum is moved manually to operative (vertical) or inoperative (horizontal) position.

The invention provides means for adjustably and detachably securing the pin or rod 29 to the card frame bar 21 or to the corresponding bar of any similar optical instrument, in such a manner that the pin or rod 29 is held against rotation about its longitudinal axis.

As here embodied, for this purpose, the pin 29 is provided at one end with a loop or eye 44, through which passes the shank of a machine screw 45 threaded into the upper end 46 of a spring clip 47. The spring clip here shown is provided with a pair of opposed gripping jaws 49 and 50, between which is located a short coil spring 51, under compression, to give the jaws gripping tension.

It will be obvious that the pin or rod 29 may be similarly attached to the bar 21, but by other suitable means within the scope of the invention, providing for sliding or horizontal movement of the septum with respect to the bar 21 and for readily attaching the septum and detaching it from said bar, such, for example, as a collar 52 adapted to slide along the bar 21, provided with a set screw 53 for securing it in fixed position on said bar. In some instances, for example where the bar is rectangular in cross section, it may be desirable to use merely a sliding collar 55 and omit the set screw, the construction being similar to the bar attaching means of the test card frame 22 shown in Fig. 1.

It will be seen that, by means of the invention, various optical testing, exercising and measuring instruments may be instantly converted into stereoscopes, and can be used for the additional purpose of testing the eyes for binocular vision, or to provide the facilities for different exercises or tests or measurements, all without interfering in any way with the use of the instrument for any particular purpose for which it may have been constructed.

The septum of the present invention can be readily placed at any desired distance from the eyes upon the card frame bar, and, when in vertical or operative position, limits the vision of the right eye to the right half of the test card, and the vision of the left eye to the left half of the card. A patient being tested can therefore read a whole line of letters extending horizontally across the card only when binocular vision is present.

For the purpose of giving fusional training or muscular exercise to the eyes, the septum of the present invention is used in operative position in conjunction with a card bearing special images, letters, objects, or characters, so printed that a complete image, letter, object, or character is seen only by the proper correctional muscular exercise.

It will be apparent that various changes and modifications may be made in the invention as here described by way of exam-

ple, without sacrificing any of its advantages, and without departing from the scope of the invention as defined by the following claims.

What is claimed is:

1. A septum including a septum portion, a clamp, elements rotatably securing said septum portion to said clamp and cooperating holding members for frictionally locking said septum portion in vertical or substantially horizontal position. 70 75

2. A septum including an opaque septum portion, a device for slidably attaching said septum portion to a supporting member, and elements rotatably securing said septum portion to said attaching device including interengaging locking members for frictionally locking said septum portion in vertical and 80 horizontal positions.

3. A septum including a septum portion, a jaw clamp for attaching said septum to a support slidably in a straight line, and elements rotatably securing said septum portion to said jaw clamp including interengaging locking members for frictionally locking said septum portion in vertical and 90 horizontal positions. 95

4. In an optical instrument having a pair of lenses, a septum support, a septum including a septum portion, a spring jaw clamp for attaching said septum to said support for rectilinear movement therealong, and elements rotatably securing said septum portion to said jaw clamp including interengaging locking members for frictionally locking said septum portion in vertical and in horizontal positions, one of said locking members being resilient and having pockets extending at right angles to each other and the other of said members having an offset portion cooperating with said pockets and extending substantially in the direction of movement of said septum along said support. 100 105

5. In an optical instrument having a pair of lenses, a septum support extending in the direction of the axes of said lenses, a septum including a septum portion, an attaching element carrying said septum portion and slideable along said support, and elements rotatably securing said septum portion to said attaching element including interengaging locking members for frictionally locking said septum portion in vertical position in the plane of said septum support and also in a plane at right angles thereto, one of said locking members being resilient and having pockets extending at right angles to each other and the other of said members having an offset portion cooperating with said 110 115 120 125 pockets.

In testimony whereof I affix my signature.

BENJAMIN WOODWARD HAZELL. 130
